UNITED STATES PATENT OFFICE.

DAVED ZAKIM, OF NEW YORK, N. Y.

CLIP FOR PENS, PENCILS, AND SIMILAR ARTICLES.

1,162,843.

Specification of Letters Patent.

Patented Dec. 7, 1915.

Application filed May 27, 1915. Serial No. 30,757.

To all whom it may concern:

Be it known that I, DAVED ZAKIM, a citizen of Russia, and a resident of New York city, in the county of Bronx and State of New York, have invented certain new and useful Improvements in Clips for Pens, Pencils, and Similar Articles, of which the following is a specification.

This invention relates to a clip for pens, pencils and similar articles which is provided with a ball bearing for engagement with the garment, and comprises more particularly novel and efficient means for rotatably mounting the ball within the body of the clip, in a simple and durable manner.

In the accompanying drawing: Figure 1 is a front view of a clip embodying my invention, showing the same affixed to a fountain pen; Fig. 2 a side view thereof; Fig. 3 a longitudinal section of the clip detached; Fig. 4 a front view of the clip blank; Fig. 5 a section through the socket, and Fig. 6 a front view of a modification of the clip.

The device comprises essentially a preferably tapering finger 1, adapted to be secured at its upper end to a fountain pen or similar article 2. As shown in Figs. 1-3, the finger may for that purpose be provided with an upper split ring 3, projecting from its inner face and adapted to grasp said article, while with the construction shown in Fig. 6, it is permanently secured thereto by rivets 4.

At its lower or free end, the finger is provided with a socket 5 made in the form of a ring and arranged substantially in the plane of the finger. The ring is of concave or tapering shape in cross section and accommodates a ball 6 which is securely grasped by the socket, while capable of a universal

movement therein. By the construction described, the ball will protrude sidewise from the socket, so as to come into engagement with the garment when the pen is inserted into the pocket or removed therefrom.

Owing to the fact that the ball may freely turn in all directions, it will during such introduction or removal, always rotate on an axis at right angles to that of the finger, so that friction is avoided even though the pen be slipped into the pocket at an inclination to the vertical.

In constructing the device, there are formed on the bendable blank of the finger, two dished rings 7 and 8 (Fig. 4) arranged below one another. The ball is placed in the upper ring, and then the lower ring is bent against the inner face of the upper ring, so as to form a bipartite socket at the lower end of the finger that encompasses the ball. By bending the lower ring against the inner, and not against the outer, face of the upper ring *i. e.* against that face of the finger from which the clip attaching means project, the pressure exerted by the ball when the device is in use, will not have a tendency to spread the two moieties of the socket, so that in this way the durability of the device is insured.

I claim:

A clip for a pen or similar article, comprising a finger having upper attaching means extending from the inner face thereof, a first socket member at the base of the finger, a second annular socket member integral with the finger and bent against the inner face of the first named socket member, and a ball rotatably mounted in said members.

DAVED ZAKIM.
